(57) **CLAIM**

I claim the ornamental design for the face mask, as shown and described.

DESCRIPTION

FIG. 1 is a front elevational view of a face mask showing my new design, the strap is shown partially removed for ease of illustration;

FIG. 2 is a top view thereof;

FIG. 3 is a left side elevational view thereof taken from FIG. 1, the right side elevational view is the mirror image thereof;

FIG. 4 is a bottom view thereof;

FIG. 5 is a rear elevational view thereof; and,

FIG. 6 is a perspective view thereof.
